UNITED STATES PATENT OFFICE.

DANIEL C. HARRIS, OF VIRGINIA, MINNESOTA.

LOCK NUT.

Application filed June 1, 1923. Serial No. 565,148.

To all whom it may concern:

Be it known that I, DANIEL C. HARRIS, a citizen of the United States, residing at Virginia, in the county of Saint Louis and State of Minnesota, have invented certain new and useful Improvements in Lock Nuts, of which the following is a specification, reference being had therein to the accompanying drawing.

10 This invention relates to nuts and screw threaded bolts and more particularly to an automatic locking device for such.

The principal object is to provide an improvement over similar devices in the art.

15 Other objects and advantages of the invention will appear in the further description thereof.

Referring to the accompanying drawing forming part of this application in which 20 like reference characters indicate like parts:

Figure 1 is an elevation of a fragmental portion of a bolt having one of the improved nuts applied thereto with the locking device in operative position:

25 Figure 2 is a perspective view of the locking device or key member:

Figure 3 is an inside elevation of the nut shown in Figure 1 with the key in position:

30 Figure 4 is an outside elevation of a nut with a slightly modified arrangement of key mounting: and

Figure 5 is an edge elevation of the nut shown in Figure 4, with the key removed.

The bolt 1, used in connection with my improved locking nut, is provided with a plurality of longitudinal notches 2, preferably six or more and approximately one-half the depth of the thread of the bolt.

35 In the nut 3, shown in Figures 1 and 3, the locking key 4 is mounted upon the circumferential face of the nut adjacent the inner or impinging wall 5 thereof, though it is not of a width to engage the object being impinged as such would interfere with the

40 functioning of the key. The key is made of a flat piece of spring steel, bent to conform with one of the angular sides of the nut and made sufficiently contractile as to its opposite ends to snugly fit within the recesses formed therefor in the circumferential face of the nut.

45 The key for ordinary practical purposes will be made substantially half the width of the nut upon which it is used, and, from the inner edge of the key is formed by forcefully shearing therefrom, a depending dog

6, which, when in active position on the nut protrudes longitudinally of and within the inclined slot 7 formed on the inner face of the nut. This positioning of the key and dog 60 will cause the biting free end of the latter to protrude within the threaded portion of the nut and within the path of the thread of a bolt being applied to the nut, as clearly seen in Figure 3 of the drawing. 65

The opposite ends of the key are arched inwardly substantially as shown in Figure 2 at 8 and 9, such arched or curved terminations being designed to fit within the concaved recesses 10 and 11 respectively. However, the terminations 8 and 9 differ somewhat in that the latter has an abruptly turned up edge as at 12 which does not coincide with the wall of its respective recess, which is to permit of a sharp instrument being placed thereunder and when prying operation under the edge of the recess 10 is practiced the entire key 4 may be quickly released from operable engagement with the nut. 70 75 80

A cut-away or stepped portion is formed upon the circumferential wall of the nut intermediate of the concaved recesses 10 and 11 into which the key 4 fits with its outer surface flush with the outer wall of the nut 85 so as not to interfere in any way with the manipulation of the wrench upon the nut, or the successful operation of the same.

By this means it is evident that the nut may be successfully screwed upon the bolt 90 while the key is in position, but any attempt to unscrew the same will be opposed by the dog 6 engaging the notches 2 in the thread of the bolt, and that the nut cannot be unscrewed without removing the key, 95 this being readily accomplished with the proper type of instrument. There is obviously thus afforded a very convenient and practical form of lock nut.

In the making of the nut with the proper recesses and channels for cooperation with the spring key, I have confined myself to the most practical construction possible, in that all of such peculiarities in the formation of the nut may be accomplished by a 100 single operation and drop forging of the blank nut.

105 In Figures 4 and 5 I have shown a modification of the combination key and nut in that the blank nut is formed with the concaved recesses 10 and 11, the inclined channel 7, and the cut-away or stepped portion 13,

upon one flat face only; while upon the adjacent flat face there is formed a narrow channel 14 transverse said face, one end of which opens into the cut-away portion 13, 5 and the opposite end into the concaved recess 11; all of this peculiar shaping of the nut being adjacent one corner of the outer face of the nut, instead of the inner face, as previously described, and the ridge 15 being 10 left outside of that part of the key seat 14 is to provide against dislodgment of the key longitudinally of the axis of the nut.

In the two different forms of keys illustrated, it is evident that they are right and 15 left in respect to each other.

The principal object of not forming the channel 14 on the two adjacent flat faces of the nut is simply to avoid the additional expense in doing so, as in the manufacture of 20 the nuts these channels are milled out and fed to the machine for such purpose in a continuous row; the forming of the channel on one side only being simply sufficient to guard against accidental loss of the key. 25 Having thus described my invention, what

I claim as new and desire to secure by Letters Patent, is:

An internally screw threaded lock nut of the character described, the exterior of which is formed into a plurality of flat angularly disposed faces, a stepped or cut-away portion on two of the adjacent faces next the inner face of the nut, two concaved recesses one at each termination of the stepped portions and axially parallel with the hole in the nut, an inclined channel on the inner face of the nut one end of which terminates in the hole in the nut and the other in one of the stepped portions, and a contractile removable flat spring key having a dog intermediate of its ends protruding within the channel and into the path of the thread of the nut, substantially as described.

In testimony whereof I hereunto affix my signature in the presence of two witnesses.

DANIEL C. HARRIS.
